[57] ABSTRACT

§ 102(e) Date: Jun. 4, 1999

In a radiant heating body for a cooking location, in particular in the case of a glass ceramic plate (4), an insulating bottom (2) with an insulating annular rim portion (3) is provided in a pot member (1). A heating element (6) is arranged in an air space (5) above the insulating bottom (2). A safety temperature limiter is provided on the pot member (1). In order to achieve a low degree of switching hysteresis and to avoid an expansion bar regulator, the safety temperature limiter is in the form of a bimetal switch component (8) having a housing (9) which is fixed to the pot member (1) and in which a bimetal element (11) is disposed at the side: towards the air space (5). Provided at the annular rim portion (3) is an opening (20, 24) through which the bimetal element (11) is thermally coupled directly or indirectly to the air space (5).

FIG. 3

FIG. 4

RADIANT HEATING ELEMENT FOR A COOKING AREA

BACKGROUND OF THE INVENTION

1. Field of the Invention

The invention concerns a radiant heating body for a cooking location, in particular in relation to a glass ceramic plate, wherein an insulating bottom having an insulating annular rim portion is provided in a pot member and a heating element is arranged in an air space above the insulating bottom and a safety temperature limiter is provided on the pot member.

2. Discussion of the Prior Art

Radiant heating bodies of that kind are commercially known and are described for example in DE 35 36 981 C2. The safety temperature limiter serves to protect the glass ceramic plate from overheating. The safety temperature limiter comprises, in a tube, an expansion bar which extends in the air space above the heating element. An expansion bar regulator of that kind is a complicated and thus expensive component. Furthermore arranging the expansion bar in the air space involves a correspondingly large structural height in respect of the radiant heating body.

A glass ceramic cooking zone having an energy regulator and a bimetal regulator which is disposed laterally on the radiant heating body is described in HEA-Bilderdienst 6.2, August 1983, pages 17 and 18. The bimetal regulator is closed to start the cooking procedure. The bimetal regulator opens at a cooking zone temperature of about 125° C. In this case also safety temperature limitation is effected by means of the expansion bar sensor of the energy regulator.

SUMMARY OF THE INVENTION

The object of the present invention is to propose a radiant heating body of the kind set forth in the opening part of this specification, in which an expansion bar is not required, while affording a low degree of switching hysteresis in respect of safety temperature limitation.

In accordance with the invention the foregoing object is attained in that as a safety temperature limiter there is provided a bimetal switch component having a housing or a base plate which is fixed to the pot member. A bimetal element is disposed in the housing or on the base plate at a side towards the air space. Formed in the annular rim portion is a through-opening through which the bimetal element is directly or indirectly thermally coupled to the air space.

The bimetal switch component is an inexpensive component and results, in a simple manner, in a sufficiently low level of switching hysteresis as it reacts quickly to the heat radiation from the heating element. Severe overshooting of the temperature beyond a limit value is also avoided as a result. A further advantage of the arrangement of the bimetal switch component is that there are various simple possible ways of setting or adjusting the response temperature of the bimetal member.

A structural advantage is that the bimetal switch component has practically no influence on the structural height of the radiant heating body because it does not extend in the air space between the insulating bottom and the glass ceramic plate.

Preferably the temperature at which the bimetal element responds is greater than 300° C. That substantially suppresses the influences of the ambient temperature of the radiant heating body.

In a preferred development of the invention the function of an adjustable energy regulator is integrated into the

bimetal switch component. For that purpose, connected to the bimetal element or a switch contact which is actuatable thereby is an adjusting member with which the response temperature of the bimetal element is adjustable.

BRIEF DESCRIPTION OF THE DRAWINGS

Further advantageous configurations of the invention are set forth in the appendant claims and the following description of embodiments by way of example. In the drawing:

FIG. 1 is a plan view of part of a radiant heating body with a bimetal switch component in a first embodiment, with an annular member which is partially broken away in the drawing,

FIG. 2 is a view in section taken along line II—II in FIG. 1,

FIG. 3 is a partly sectional view of the bimetal switch component,

FIG. 4 is a view of the bimetal switch component viewing in the direction of the arrow IV in FIG. 3,

FIG. 5 is a plan view of part of a radiant heater with a bimetal switch component in a second embodiment,

FIG. 6 is a view in section taken along line VI—VI in FIG. 5,

FIG. 7 shows an embodiment with integrated power regulation, and

FIG. 8 diagrammatically shows a circuit diagram.

DETAILED DESCRIPTION OF PREFERRED EMBODIMENTS

A radiant heating body has a pot member 1 in which is disposed an insulating bottom 2 comprising thermally and electrically insulating material. Provided in the pot member 1 is a thermally and electrically insulating annular rim portion which in the illustrated embodiments is formed by a separate annular member 3. In the embodiment shown in FIGS. 1 and 2 the insulating bottom 2 and the annular rim portion could also be formed in one piece. Between the insulating bottom 2 and a glass ceramic plate 4 which can be fitted on to the radiant heating body is an air space 5 in which a heating element 6 which radiates visibly in operation is arranged. In the illustrated embodiments the heating element shown is in the form of a heating coil laid in a spiral configuration. It is however also possible to provide other radiating heating elements, for example comprising flat wire or heating conductor foil or a halogen radiating arrangement. Disposed externally on the pot member 1 is a connecting plug 7 for the electrical connection of the heating element 6.

Provided as the safety temperature limiter is a bimetal switch component 8 whose ceramic housing 9 is closed by a metal base plate 10. In the interior of the housing 9 a bimetal element 11 bears in heat-conductive relationship against the base plate 10. The bimetal element 11 can be in the form of a snap disc. The bimetal element 11 is operatively connected to an electrical switch contact 14 by way of a ceramic pin 12 which is supported in a guide 13. Current connections 15 of the switch contact 14 are passed outwardly out of the housing 9 (see FIG. 3).

At both sides at a spacing from the base plate 10 the housing 9 has grooves 16 with which the housing 9 can be fitted into an opening 17 in the pot member 1, with the edges of the opening 17 engaging into the grooves 16. The switch component 8 is thereby fixed to the pot member 1 in a simple fashion, while thermal decoupling of the bimetal element 11 from the pot member 1 which usually comprises sheet metal

and which is thus heat-conducting is achieved by way of the ceramic housing **9**. The bimetal switch component **8** can also be fixed to the pot member **1** in another fashion, for example by means of a bracket.

In the assembled condition (see FIGS. 1 and 2, and FIGS. 5, 6 and 7), the base plate **10** lies in a recess **18** which is open towards the pot member **1**, without touching the pot member **1**, which promotes thermal decoupling of the base plate **10** from the pot member **1** and thus from its ambient temperature. In another construction the base plate **10** can bear against the pot member **1** and/or can be fixed thereto by being engaged into same. In that case, contact in point form or in line form is adopted, for example by means of knobs or ridges, to provide for the thermal decoupling effect, that is to say to provide for poor thermal coupling.

The current connections **15** are disposed outside the pot member **1**. Clips **19** hold the base plate **10** to the housing **9**. They do not represent substantial thermal bridges.

In the embodiment of FIGS. 1 and 2 direct thermal coupling is involved between the air space **5** and the bimetal element **11** which is connected to the base plate **10** in heat-conducting relationship. For that reason, in the region of the base plate **10** and therewith the bimetal element **11** the annular member **3** has a through passage **20**. Heat radiation from the heating element **6** passes through the passage **20** and directly on to the base plate **10**. If even more direct coupling is wanted, then the base plate **10** can have one or more openings in the region of the bimetal element **11**. FIG. 4 shows such an opening at **21**.

The embodiment shown in FIGS. 5 and 6 provides for indirect thermal coupling of the air space **5** to the bimetal element **11**. For that purpose a heat-conducting portion **22** is provided on the base plate **10**. The portion **22** has a limb **23** which extends through a through passage **24** which is provided between the annular member **3** and the insulating bottom **2**. Adjoining the limb **23** is a limb **25** which is disposed in the air space **5** beside the heating element **6**. The limb **25** is disposed approximately where the passage **20** is to be found in the embodiment shown in FIGS. 1 and 2. The heat-conducting portion **22** can be formed in one piece with the base plate **10** or it can be in the form of a separate member which is secured thereto.

Reception of the thermal radiation which emanates from the heating element **6** can be improved if the limb **25** in the embodiment shown in FIGS. 5 and 6 or the base plate **10** in the embodiment shown in FIGS. 1 and 2 is coloured, preferably blackened, matted and/or roughened, at the surface which is towards the heating element **6**. In the embodiment shown in FIGS. 1 and 2 the bimetal element **11** itself is additionally also coloured, preferably blackened, and/or matted, opposite the opening **21**. In order to provide for rapid reaction of the bimetal element **11** to the radiant heat from the heating element **6**, it is also advantageous if the surface, that is exposed to the radiation, of the limb **25** or the base plate **10** is of large area, if the heat-conducting portion **22** or the base plate **10** is of small mass and comprises a material which is a good conductor of heat.

The bimetal temperature at which the bimetal element **11** switches is preferably in the range of between 300° C. and 500° C. It is advantageous to choose such a high temperature because then the ambient temperature of the pot member **1** scarcely has any influence on the switching characteristics. The above-described direct or indirect coupling arrangements make it possible to provide for adaptive adjustment such that the bimetal member reliably opens the switch contact **14** at a temperature which is critical for the glass

ceramic plate **4** and which is at a given limit value, depending on the construction involved, between 530° C. and 630° C., at the top side of the glass ceramic plate, without involving excessive overshooting of the limit temperature.

Switching hysteresis of the switch contact **14** can also be kept to a desired low value, for example 30 K, by virtue of the described coupling arrangements.

Besides being influenced by the above-described measures, opening of the switch contact **14** at the limit temperature of the glass ceramic plate **4** can also be influenced by the following steps:

- a) the bimetal element **11** is suitably pre-shaped;
- b) the spacing of the base plate **10** or the bimetal element **11** from the heating element **6** is suitably selected;
- c) the size of the passage **20** is suitably adopted; and
- d) the position of the base plate **10** or the bimetal element **11** is related to the hottest region of the heating element **6**.

The bimetal switch component **8** may also have a second switch contact **26** which is controllable by the bimetal element **11** or a further bimetal element **11**, possibly a further bimetal switch component **8**. A per se known optical residual heat display, for example a glow lamp **27**, may be operated

with that second switch contact **26** (see FIG. 8). It is also possible for two bimetal switch components to be arranged on the pot member **1** in the described manner, in which case one serves for safety temperature limitation and the other is adjusted to a lower temperature, for example less than 100° C., for the residual heat display.

In the embodiment shown in FIG. 7 the bimetal switch component **8** has a rotatable adjusting member **28** connected to a rotary handle which can be operated by the user. The temperature at which the switch contact **14** or a third switch contact **29** (see FIG. 8) opens below the limit temperature of the glass ceramic plate **4** can be adjusted by means of the adjusting member **28** which acts on the bimetal element **11** or the switch contact **14**. Thus, besides the function of providing for safety temperature limitation, the bimetal switch component **8** also implements the function of energy regulation for the cooking hob with a low level of switching hysteresis and a small degree of overshoot.

What is claimed is:

1. A radiant heating body for a cooking location, in particular in relation to a ceramic glass plate, wherein an insulating bottom having an insulating annular rim portion is provided in a pot member and heating element is arranged in an air space above the insulating bottom and a safety temperature limiter is provided on the pot member, wherein the safety temperature limiter comprises a bimetal switch component **(8)** having a ceramic housing **(9)**, a metal base plate **(10)** closing said housing, said housing being fitted through grooves **(16)** into an opening **(17)** formed in the pot member **(1)**, a bimetal element **(11)** disposed in the housing **(9)** in electrical contact with the base plate **(10)**, at a side facing towards the air space **(5)**, and the annular rim portion **(3)** being provided with a through opening **(10, 24)** through which the bimetal element **(11)** is thermally coupled selectively directly or indirectly to the air space **(5)**, wherein the current connections **(15)** of the switch contact **(14)** of the bimetal switch component **(8)** lie outside the pot member **(1)**.

2. A radiant heating body according to claim 1 characterised in that the bimetal element **(11)** bears in the housing **(9)** in the heat-conductive relationship against said metal base plate **(10)** which is disposed within the pot member **(1)** between the pot member **(1)** and the annular rim portion **(3)**.

3. A radiant heating body according to claim 1, characterised in that the base plate (10) bears against the pot member (1) in point contact.

4. A radiant heating body according to claim 1, characterised in that in the region of the bimetal element (10) the base plate (10) has at least one opening (21) in alignment with said bimetal element (11).

5. A radiant heating body according to claim 1 characterised in that the base plate (10) and the bimetal element (11) are disposed opposite the opening (20) in the annular rim portion (3) and are exposed through said opening (20) to the radiant heat emanating from the heating element (6).

6. A radiant heating body according to claim 1 characterised in that a heat-conducting portion (22) is formed or fixed on the base plate (10) and extends through the passage 15

7. A radiant heating body according to claim 6 characterised in that the heat-conducting portion (22) is disposed in the air space (5) with respect to the plane of the cooking hob beside the heating element (6).

8. A radiant heating body according to claim 1, characterised in that at the surface towards the air space (5) and the heating element (6) the base plate (10), the bimetal element (11) and the heat-conducting portion (22) are selectively colored, matted and roughened, to improve reception of the 25 radiant heat emanating from the heating element (6).

9. A radiant heating body according to claim 1 characterised in that the bimetal element (11) switches at a temperature above 250° C.

10. A radiant heating body according to claim 1 characterised in that the bimetal switch component (8) is fixed by means of the base plate (10) to the pot member (1), wherein the base plate (10) bears against the pot member (1) only in point form or line form.

11. A radiant heating body according to claim 1 characterised in that an adjusting member (28) for energy regulation is connected to the bimetal element (11) or a switch contact (14, 29) actuatable thereby.

12. A radiant heating body according to claim 1 characterised in that the bimetal switch component (8) has a second switch contact for a residual heat display.

13. A radiant heating body according to claim 1 characterised in that arranged on the pot member (1) is a further bimetal switch component having a switch contact for the residual heat display.

14. A radiant heating body according to claim 12 or claim 13 characterised in that the bimetal element for the residual heat display switches at a temperature of less than 100° C.

15. A radiant heating body according to claim 1, characterised in that the base plate (10) bears against the pot member (1) in a linear contact.
